UNITED STATES PATENT OFFICE.

JAMES H. MACDERMID AND HAROLD S. WELLS, OF DETROIT, MICHIGAN, ASSIGNEES TO
DODGE BROTHERS, OF DETROIT, MICHIGAN, A CORPORATION OF MICHIGAN.

OVEN.

1,334,465.

Specification of Letters Patent. Patented Mar. 23, 1920.

Application filed Mar. 26, 1918. Serial No. 224,728.

To all whom it may concern:

Be it known that we, JAMES H. MACDERMID and HAROLD S. WELLS, citizens of the United States, residing at Detroit, Michigan, have invented certain new and useful Improvements in Ovens, of which the following is a clear, full, and exact description.

This invention relates to an improvement in ovens of the type in which the heating effect is obtained by direct combustion internal to the oven. Its chief purpose is to provide means for conserving the heat generated in the oven with the idea of economy in fuel. Another purpose is to provide efficient means for supplying the air to support combustion so that a minimum amount of cold air is required.

Another purpose is to provide suitable means for controlling the dilution of the air in the oven, produced both by the combustion required for heating and also by any gases evolved by the contents of the oven as they are heated.

Still another purpose is to provide means for producing a constant circulation throughout all parts of the oven so that a uniform temperature may be maintained.

These being among the objects of the present invention the same consists of certain features of construction and combinations of parts to be hereinafter described and then claimed with reference to the accompanying drawings which illustrate a suitable embodiment of the invention having the above and other objects in view.

Figure 1 is a plan view of an oven embodying the present invention.

Fig. 2 is a longitudinal elevation of the same.

Fig. 3 is a cross section taken on the line 3-3 of Fig. 2.

Fig. 4 is a cross section taken on the line 4-4 of Fig. 2.

Fig. 5 is a plan view of one of the air distributing tubes.

The oven 11 may be constructed of any suitable insulating and heat resisting material. It may also be provided with any desired arrangement for charging and discharging, such, for example, as a conveyer system operating through the openings 12 in the floor of the oven, which is here shown as constituted by the floor 8 of the building in which the oven is located, but as the

construction of the walls of the oven and the apparatus for charging and discharging are not features of the present invention, they will not be described.

To heat the oven, horizontal pipes 13 are spaced at intervals along the bottom of the oven and, in the installation shown, are laid transversely for substantially the full width of the oven. These pipes are provided with rows of small openings on their upper sides and serve as burners for the gas which is supplied through them.

At one side of the oven the pipes forming the gas burners are extended outward through the wall of the oven and connected to the manifold 24. Suitable connections for supplying the gas to this manifold and apparatus for controlling the quantity and pressure of the gas supplied may also be provided, but are not shown in the drawings as they form no part of the present invention.

Adjacent to the gas burners just described are the air distributing tubes 14 which are arranged to extend parallel to the gas burners. As shown in Fig. 5, these tubes are provided with a number of small openings in their upper sides so that they deliver streams of air in proximity to the jets of gas issuing from the gas burners. For supplying air to the distributing tubes, the ducts 15, preferably of sheet metal, are provided extending longitudinally of the oven on either side and being connected alternately to the distributing tubes.

These air ducts are connected to the risers 16 which are, in turn, connected at their upper ends to the discharge openings of the blowers 17. The suction sides of these blowers are connected to the ducts 18 extending along the sides of the oven near the top. These ducts are provided with branches 19 connecting with openings in the top of the oven so that the blowers draw a mixture of heated air and other gases from the top of the oven and discharge it through the system of ducts just described into the distributors at the bottom of the oven. In addition to the air drawn from the top of the oven, a certain amount of fresh air is also admitted through the branches 20 into the ducts 18, these branches being provided with dampers for regulating the amount of fresh air admitted.

Additional openings 21 in the top of the

oven are connected to ducts 23 leading outside of the building in which the oven is located, these ducts being provided with exhaust fans 22 for assisting the flow of air and being shown as extending through the side wall 26 of the building. In some installations exhaust fans would probably not be required, but, in the particular application of the invention illustrated, the shape 10 of the ventilating duct is such that the use of the fans is desirable.

By properly controlling the speed of the fans and blowers connected to the circulating system and by regulating the dampers 15 in the inlets 20, it is possible to reduce the amount of air admitted to the point where the amount of oxygen supplied is just sufficient to support combustion and the large surplus of air required is ovens of previous 20 types, in which the air is not efficiently distributed to the burners, is avoided. With the amount of fresh air supplied reduced to the required minimum, a corresponding reduction in the amount of fuel required is 25 effected since all the air admitted has to be raised from the temperature existing outside to that in the interior of the oven. The arrangement of the present invention also presents the advantage of an efficient circulation 30 throughout all parts of the oven since all the air enters the oven through the distributing tubes which are spaced at close intervals over practically the entire floor. From the distributors the air then rises to 35 the top of the oven where the greater part of it is drawn through the ducts 18 and recirculated to the bottom of the oven, while the remainder passes out through the ducts 23.

40 The fact that the cold air is admitted in close proximity to the burners is also of advantage in that this air is thus heated immediately on entering the oven and before it has any chance to come in contact with 45 the articles being treated.

Another feature of the arrangement which assists in heating the incoming air before it comes in contact with the contents of the oven is the location of the ducts 15 inside 50 the walls of the oven so that they are exposed to the heat and, consequently, serve to warm the incoming air before it reaches the transverse distributing tubes.

What we claim as new is:

55 1. Means for heating an oven, comprising a series of pipes for supplying gas, said pipes having perforations spaced longitudinally to constitute gas burners, and a second series of pipes, also provided with perforations and arranged in proximity to said further series of pipes for supplying air in jets to the atmosphere in which the flames of said burners burn in proximity to the point of combustion.

60 2. Means for heating an oven, comprising

pipes disposed in parallelism and provided with perforations, part of said pipes serving to supply gaseous fuel and to constitute burners and part to supply air to the atmosphere in which the flames of said burners 70 burn, said fuel pipes being in proximity to said air pipes.

3. In an oven, gas burners in proximity to the floor of said oven and distributed substantially throughout the entire floor space 75 of said oven and means acting in proximity to the flames of said burners for supplying jets of air to the atmosphere in which said flames burn.

4. In combination with an oven and burners within said oven, ducts internal to said oven, and adapted to absorb heat, said ducts serving to pre-heat the air supplied for combustion, and tubular members provided with perforations for delivering said air in jets to 80 the oven atmosphere in proximity to the flames of said burners.

5. In combination with an oven and burners within said oven, internal ducts extending longitudinally of said oven and transverse branches connecting with said ducts, said ducts serving to pre-heat air supplied to said branches and said branches being arranged to deliver said air in jets spaced longitudinally of said branches and in proximity 90 to the flames of said burners.

6. In combination with an oven, means internal to said oven for supplying gaseous fuel in jets, longitudinal ducts internal to said oven and transverse branches connecting with said ducts, said ducts being constructed to deliver air in jets in proximity 100 to the jets of gaseous fuel supplied by said means.

7. The combination with an oven having 105 internal burners arranged along the floor thereof, of means for withdrawing air from the top of said oven and discharging it in jets adjacent to the flames of said burners.

8. The combination with an oven having 110 internal burners arranged along the floor thereof, of means for withdrawing air from the top of said oven and discharging it in jets adjacent to the flames of said burners, said means having provision for mixing with 115 said air a portion of outside air.

9. The combination with an oven having internal burners arranged along the floor thereof, of means for withdrawing air from the top of said oven and discharging it in 120 jets adjacent to the flames of said burners, said means having provision for mixing with said air a portion of outside air, and being arranged within said oven to preheat said mixture before discharge.

125 10. The combination with an oven having gas jets distributed over the floor thereof and constituting burners for heating said oven, of means for withdrawing air from the upper part of said oven and discharging 130

it in jets adjacent to the gas jet flames of the respective burners.

11. In an oven, the combination with burners providing a large number of individual flames distributed substantially throughout the area of one wall of said oven, of means for supplying air to the flames of said burners for supporting combustion, comprising means for discharging said air in a large number of individual jets likewise distributed substantially throughout the area of said wall of said oven.

12. In an oven, the combination with burners providing a large number of individual flames distributed substantially throughout the area of one wall of said oven, of means for supplying air to the flames of said burners for supporting combustion, comprising means for discharging said air in a large number of individual jets likewise distributed substantially throughout the area of said wall of said oven, said means being arranged to take said air from a remote part of said oven and having provision for also introducing a portion of air from outside said oven.

13. The combination with an oven, of a series of burners spaced along the floor of said oven, both longitudinally and transversely thereof, and means for withdrawing air from the top of said oven and delivering it at points on the floor of said oven adjacent to said burners and likewise spaced both laterally and longitudinally of said oven floor.

14. The combination with an oven and gas jets within said oven spaced both laterally and longitudinally of the floor thereof for heating said oven, of means for delivering air in jets in proximity to said gas jets, said air jets being also spaced both laterally and longitudinally of the floor of the oven.

15. The combination with an oven and gas

jet pipes extending transversely of the floor of said oven and spaced longitudinally thereof for heating said oven, of a series of air jet pipes alternating with the gas jet pipes for delivering air in proximity to said gas jets, and ducts within said oven and heated by the heat thereof for delivering air to said air jet pipes, said ducts being arranged upon opposite sides of said oven and successive air jet pipes being connected to opposite ducts.

16. The combination with an oven and a series of parallel gas jet pipes arranged transversely of the floor of said oven and spaced longitudinally thereof for heating said oven, of a series of air jet pipes alternating with the gas jet pipes and arranged to deliver air in proximity to said gas jets, and means comprising ducts within said oven and arranged to be heated by the heat thereof for conveying air from points in said oven remote from said jets to said air jet pipes.

17. The combination with an oven and a series of parallel gas jet pipes arranged transversely of the floor of said oven and spaced longitudinally thereof for heating said oven, of a series of air jet pipes alternating with the gas jet pipes and arranged to deliver air in proximity to said gas jets, and means comprising ducts within said oven and arranged to be heated by the heat thereof for conveying air from points in said oven remote from said jets to said air jet pipes, and means for mixing fresh air with said oven air on its way to said air jet pipes.

Signed at Detroit, Mich., this 23rd day of March, 1918.

JAMES H. MACDERMID.
HAROLD S. WELLS.

Witnesses:

ALFRED H. KNIGHT,
GEO. W. HERGENROETHER.

It is hereby certified that in Letters Patent No. 1,334,465, granted March 23, 1920, upon the application of James H. Macdermid and Harold S. Wells, of Detroit, Michigan, for an improvement in "Ovens," errors appear in the printed specification requiring correction as follows: Page 2, line 19, for the word "is" read *in*; same page, line 61, claim 1, for the word "further" read *first*; same page, line 73, claim 3, for the word "poximity" read *proximity*; and that the said Letters Patent should be read with these corrections therein that the same may conform to the record of the case in the Patent Office.

Signed and sealed this 27th day of April, A. D., 1920.

[SEAL.]

M. H. COULSTON,

Acting Commissioner of Patents.
